UNITED STATES PATENT OFFICE.

NICHOLAS ALBRECHT, OF PHILADELPHIA, PENNSYLVANIA, ASSIGNOR TO FRED PEARSON & COMPANY, INCORPORATED, OF MANAYUNK, PENNSYLVANIA.

DESIGN FOR A CUT PILE FABRIC.

47,842.

Specification for Design.

Patented Sept. 21, 1915.

Application filed July 14, 1915. Serial No. 39,910. Term of patent $3\frac{1}{2}$ years.

To all whom it may concern:

Be it known that I, NICHOLAS ALBRECHT, a citizen of the United States, residing at Philadelphia, in the county of Philadelphia and State of Pennsylvania, have invented a new, original, and ornamental Design for Cut Pile Fabrics, of which the following is a specification, reference being had to the accompanying drawing, forming a part thereof.

The figure is a plan view of a portion of a cut pile fabric, showing my new design.

I claim:

The ornamental design for a cut pile fabric, as shown.

NICHOLAS ALBRECHT.

Witnesses:

C. R. ZIEGLER,
S. W. FOSTER.
